A. Leonard,
Casting Thimble Skeins, &c.
No. 6,688. Patented Feb. 24, 1857.

UNITED STATES PATENT OFFICE.

ANDREW LEONARD, OF KENOSHA, WISCONSIN.

IMPROVEMENT IN CASTING SKEINS FOR WAGONS.

Specification forming part of Letters Patent No. 16,688, dated February 24, 1857.

To all whom it may concern:

Be it known that I, ANDREW LEONARD, of the city and county of Kenosha, in the State of Wisconsin, have invented a new and useful method of molding and controlling green-sand cores (made in whole patterns) for thimble-skeins or other hollow conical castings by means of long bars acting in the double capacity of core-bars and of adjusting or sustaining bars, whereby I secure the true position of the cores in the center of their molds after the patterns are withdrawn, and make the castings both seamless and true when they come from the sand, and thereby preserving the chill or feather on the surface of the metal, which (being hard) reduces the friction and increases the wear of the skein, while at the same time it enables me to mold four or more patterns in one flask, each pattern leaving its own core of green sand in vertical position, and thus materially lessening the quantity of sand usually required and cheapening the cost of labor in molding; and I do hereby declare the following to be a full and clear description of the same, reference being had to the accompanying drawings, which make a part of this specification.

Figure 1 is a sectional elevation of an inverted pattern, *b*, sustained by a skeleton flask, *o*, while the core and core-bar *a* are molded up in green sand *c*, as well as sections 1 and 2 of the flask, and showing also the bottom board, *d*, with the end of the bar *a* extending through it. *t* shows the loose collar which forms the mold for the flange *p* on the skein. Fig. 2 represents a sectional elevation of a flask and mold after the pattern has been withdrawn, showing the difficulty heretofore existing, and which has prevented the making of hollow conical castings from whole patterns molded in a vertical position, leaving their own cores of green sand, which difficulty is seen at *s*, the top of the core having sprung against one side of the mold. Fig. 3 shows the method of adjusting the core by hand outside of the flask at *e*; and Fig. 4 shows the extension of section 2 of the flask, with the end of the core-bar entirely molded up in solid sand, so as to prevent the core from springing out of the center of the mold when the pattern is wrapped and withdrawn.

The nature of my invention consists in first molding the cores for hollow conical castings around one end of long core-bars inserted in

the hollow of whole patterns, and afterward molding solid sand around that portion of the same bars which extends beyond the base of the pattern, so as to unite the core with the sand which is to form a base for it to stand upon when the flask is reversed, by which means the long core-bar *a* (shown in all the figures) enables me to mold thimble-skeins for wood axles and other hollow conical castings from whole patterns, leaving their own cores of green sand, which are secured in the center of their molds after the patterns are withdrawn by the long bars, as shown either in Fig. 3 or Fig. 4. The core-bar *a*, thus acting in the double capacity of a core-bar and of an adjusting or sustaining bar, overcomes the difficulty heretofore found to exist of the liability of the core (when made of green sand) to spring out of true in wrapping or withdrawing the pattern, as shown in Fig. 2, and enables me to make seamless castings by molding whole patterns in a vertical position, using green sand for the entire mold and core, by which means I mold a full set of wagon-skeins in each flask and avoid the risk of losing the castings, which is so common in using divided patterns and dry-sand cores as heretofore.

To enable others to make and use my invention, I remark that I first provide a skeleton flask, *o*, fitted to receive an inverted hollow conical pattern, *b*, as shown in Fig. 1. A loose collar is seen at *t*. This forms the mold *p* for a flange upon the skein. The pattern being thus held, the core-bar *a* is inserted and the core molded around it with green sand, leaving the long bar standing out from the base of the pattern. Section 1 of the flask may be molded up around the outside of the pattern *b* to the center of the head at *g*, where a parting is made in the sand. Section 2 of the flask is then molded up with solid sand around that portion of the bar standing out from the core, which is thus united with its own base as one body of sand, as seen in all the figures. The core-bar *a* in Figs. 1, 2, and 3 extends through the bottom board, *d*, so as to control the core or to adjust it (when necessary) outside of the flask by the hand, as shown in Fig. 3.

Fig. 2 shows the flask (which has been reversed) and the mold after the pattern has been molded up in section 3 and withdrawn, exhibiting the core inclined against the side of the mold at *s*; and Fig. 3 shows the core-bar

in the hand at *e*, which is in the act of adjusting the core, as seen at *s*.

Fig. 4 shows the extension of section 2 of the flask with the entire end of the core-bar *a* molded up in solid sand. It will be seen that this, being properly done, will prevent the core from springing or inclining from the center of the mold when the pattern is wrapped and withdrawn. *c* represents the green sand which forms the entire mold and core. The cope, with the sprue, is not shown, it not being considered necessary, as it is well understood. In withdrawing the pattern it will be seen that section 3 of the flask lifts from the collar at *f* and section 1 from the bead at *g*, carrying with it the loose collar *t*. The pattern *b* is then wrapped and worked loose and lifted from the core, leaving it standing on its own base, which, being small relatively with its length, is liable to spring out of its true position in the mold, as seen in Fig. 2. The cope being left off enables me to see the core at *s* and to adjust it by the hand, as shown at *e*, Fig. 3, when the core-bar is not entirely molded up.

The effect of this method of molding green-sand cores around one end of long bars and of securing their true positions in their molds by the other ends of the same bars, as shown in

Figs. 3 or 4, is materially to cheapen the cost of molding and casting hollow conical castings, and also to make them seamless and true without chipping or turning, while the quality of the castings is much improved.

Having thus fully described and shown my invention, what I claim as new, and which I desire to secure by Letters Patent of the United States, is—

The method, substantially as set forth, of molding and casting thimble-skeins and other hollow conical castings in a vertical position from whole patterns, leaving their own cores of green sand, which were molded in the hollow of the patterns around one end of long core-bars, so arranged and combined with the cores and with the solid sand in the flask as to have the other end of the same bars sustain the cores, or to render them adjustable by hand after the patterns are withdrawn and the mold completed, as specified, and of thus insuring the true position of the cores in the center of their molds and making the castings perfectly true and seamless direct from the sand, substantially as described and shown.

ANDREW LEONARD.
